DWELLING

Ned H. Johansen, 3040 E. 4550 S., Salt Lake City, Utah

Filed July 24, 1961, Ser. No. 66,049

Term of patent 14 years

(Cl. D13—1)

FIG. 3

FIG. 4

I claim:

The ornamental design for a dwelling, substantially as shown.
